UNITED STATES PATENT OFFICE.

MARTIN NYSTROM, OF CHICAGO, ILLINOIS.

DESIGN FOR A SOUND-BOX CASING.

Application filed June 22, 1926. Serial No. 18,141. Term of patent 7 years.

To all whom it may concern:

Be it known that I, MARTIN NYSTROM, a citizen of the United States, residing at Chicago, county of Cook, State of Illinois, have invented a new, original, and ornamental Design for Sound-Box Casings, of which the following is a specification, reference being had to the accompanying drawing, forming part thereof.

Figure I is a front elevational view of a sound box casing showing my new design, and Figure II is a side elevational view of the same.

I claim:

The ornamental design for a sound box casing, substantially as shown.

MARTIN NYSTROM.
